US00D848247S

(12) **United States Design Patent** (10) **Patent No.:** **US D848,247 S**
(45) **Date of Patent:** **** May 14, 2019**

(54) **CABLE HOOK**

(71) Applicants: **Aryn Gilenson**, Champaign, IL (US);
Ron Smith, Lemont, PA (US)

(72) Inventors: **Aryn Gilenson**, Champaign, IL (US);
Ron Smith, Lemont, PA (US)

(**) Term: **15 Years**

(21) Appl. No.: **29/633,990**

(22) Filed: **Jan. 17, 2018**

(51) LOC (11) Cl. **08-05**

(52) U.S. Cl.

USPC **D8/370**
